F. KOSKUL.

CORNICE.

No. 18,448.

Patented July 10, 1888.

UNITED STATES PATENT OFFICE

FREDERICK KOSKUL, OF WILLIAMSPORT, PENNSYLVANIA.

DESIGN FOR A CORNICE.

SPECIFICATION forming part of Design No. 18,448, dated July 10, 1888.

Application filed March 17, 1888. Serial No. 267,593. Term of patent 14 years.

To all whom it may concern:

Be it known that I, FREDERICK KOSKUL, of Williamsport, Lycoming county, Pennsylvania, have invented and produced a new and original Design for a Cornice or Molding, of which the following is a specification.

The accompanying photograph represents my design in plan or face view.

My design consists in the series of bars A, having rounded surfaces. Transversely to said bars and extending along the opposite extremities thereof appear moldings B and C. Thus

the molding B shows two flat surfaces, D and E, the surface D being inclined. The molding C shows two flat surfaces, F and G, and between them a rounded surface, H.

I claim—

The design for a cornice, substantially as herein shown and described.

FREDERICK KOSKUL.
